UNITED STATES PATENT OFFICE.

HARRY E. CAMPBELL, OF NEW YORK, N. Y., ASSIGNOR TO CAMPBELL METAL WINDOW CORPORATION, OF BALTIMORE, MARYLAND, A CORPORATION OF MARYLAND.

SUSPENSION MEANS FOR VERTICALLY-SLIDING SASHES.

Application filed May 12, 1922. Serial No. 580,289.

To all whom it may concern:

Be it known that I, HARRY E. CAMPBELL, a citizen of the United States, residing at New York, in the county of New York and State of New York, have invented a certain new and useful Improvement in Suspension Means for Vertically-Sliding Sashes, of which the following is a specification.

The invention is suspension means for counterweighted metal sashes vertically sliding in frames, and relates more particularly to the type of metal window shown in U. S. Letters Patent No. 1,241,090, granted to me September 25, 1917.

16 The invention consists, first, in the construction whereby the ends of the suspension chains are connected to the extension plates on the side rails of said sashes, and second, to the arrangement of partitions hinged at one vertical edge and disposed within the counterweight chamber in the frame jambs, whereby the counterweights are separated from one another by a yielding barrier which prevents frictional resistance due to contact of said counterweights with one another, or such as would occur were a fixed barrier present.

In the accompanying drawings—

Fig. 1 is a vertical section of my window frame and sashes on the line 1, 1 of Fig. 2. Fig. 2 is a horizontal section of the same on the line 2, 2 of Fig. 1. Fig. 3 is a vertical section of the same on the line 3, 3 of Fig. 2. Fig. 4 is a perspective view of the hook formed in one of the sash extension plates, with the connecting device for the suspension chain in place therein.

Similar numbers and letters of reference indicate like parts.

40 As shown in my aforesaid Letters Patent, the vertically sliding sashes 5, 6 are here provided with metal extension plates 7, 8 laterally projecting from the side rails and entering vertical gaps 9, 10 in the inner wall of each jamb. The sashes are respectively counterbalanced by the weights 11, 12, the flexible suspension members or chains 13, 14 connected to said sashes and said weights passing over suitable pulleys 15, 16 disposed within the lintel 17, said weights being disposed in the jambs.

45 The suspension chains 13, 14 are connected to the extension plates of the sashes in the following manner—(see Fig. 4). In the vertical edge of each extension plate is

formed a recess A of substantially the shape shown so as to produce a downwardly turned hook B. The attaching device C is in loop form having parallel arms D, in each of which is a vertical slot E of sufficient length and area to pass over the downwardly turned portion of the hook B and become received in the portion of the recess between said hook portion and the body of the plate. The width of the slotted arms is preferably greater than that of the intervening loop F, and the device is preferably of spring metal, so that when seated in place, as shown in Fig. 4, said arms will be somewhat compressed together and so bear resiliently against the adjacent vertical edges of said recess. The end link G of the suspension chain receives the loop F, or is attached thereto in any suitable manner. In this way I produce a very simple and cheap mode of attachment for the suspension chains and also one which ensures that said chains shall be wholly enclosed in the jambs.

50 In order to save metal and to make the jambs as light and as small as possible, the necessary cross sectional area of the chamber therein in which the counterweights travel up and down has been reduced by bringing the weights quite close together; and in order to prevent their frictional contact in passing one another, a fixed barrier or partition has been interposed between them. Where, as is commonly the case, the weights are merely rough castings more or less irregular in shape with varying small surface projections, in event of the window-frame becoming a little out of plumb (as may happen through imperfect setting of said frame or settling of the wall in which the frame is located), one or the other of the pair of weights may swing into contact with said fixed partition, and considerable frictional resistance may follow which opposes the desired free movement of said weights. I obviate this trouble by hinging the vertical partition H, which lies within the jamb and extends between the weights, to the inner jamb wall, as shown at I. A simple form of hinge, which I have successfully used and here show, comprises a bracket J bolted to the jamb wall and carrying a curved arm K which extends through an opening near the edge of the partition. In case either weight swings into contact with the hinged partition, said partition then yields suffi-

105 110

ciently practically to prevent the frictional resistance to the movement of the weight before noted.

I claim:

5. 1. Suspension means for vertically sliding sashes, comprising suspended counterweights for said sashes, hollow jambs receiving said counterweights, and, within said jambs and interposed between said counterweights, partitions, each hinged at one vertical edge.

15. 2. Suspension means for vertically sliding sashes, each having lateral extension plates entering vertical gaps in the inner walls of the frame jambs, comprising flexible suspension members for said sashes and sash counterweights connected to said members, downwardly turned hooks formed integrally in the vertical edge of each extension plate, and looped metal plates having in their arms 20 slots engaging said hooks; the said looped plates receiving the free ends of said flexible suspension members.

25. 3. The combination of claim 2, further including that the said looped plates are of spring metal, the said arms being normally separated at their ends to a width greater than that of the spaces within the hooks, whereby, when seated in said hooks, said

arms are compressed together to bear resiliently against the inner vertical edges of 30 said hooks.

4. Suspension for a vertically sliding sash having lateral extension plates entering gaps in the window-frame, comprising downwardly turned hooks formed integrally in 35 the vertical edges of said extension plates, and means for connecting the ends of flexible suspension members to said hooks.

5. Suspension means for vertically sliding sashes disposed in hollow jambs, comprising 40 flexible suspension members secured to said sashes, counterweights carried by said suspension members, the said counterweights and suspension members being enclosed in said jambs, and partitions in said jambs interposed between said counterweights and extending from top to bottom of said jambs, each partition being hinged at one vertical edge to a wall of its containing jamb.

In testimony whereof I have affixed my 50 signature in presence of two witnesses.

HARRY E. CAMPBELL.
